UNITED STATES PATENT OFFICE.

CHESTER A. BAKER, OF OMAHA, NEBRASKA.

ELASTIC-FLUID COMPRESSOR.

Application filed May 10, 1924. Serial No. 712,332.

To all whom it may concern:

Be it known that I, CHESTER A. BAKER, a citizen of the United States, residing at Omaha, in the county of Douglas and State 5 of Nebraska, have invented certain new and useful Improvements in Elastic-Fluid Compressors, of which the following is a specification.

My invention relates to compressors for 10 elastic fluids such as air, ammonia, sulphur dioxide, and the like. It is the object of my invention to provide in a compressor of this class an improved valve mechanism, or means for controlling the admission and discharge of the uncompressed and compressed 15 elastic fluid to and from the cylinder. A further object of my invention is to provide a valve mechanism of this class in which repair of, and replacement of parts may be 20 reduced to a minimum. A further object is to provide a valve mechanism which may be operated at high speed without causing objectionable pounding and wear of the moving parts. A further object is to provide an 25 elastic-fluid compressor which may be arranged to deliver the compressed fluid up to a predetermined maximum pressure, and then to automatically cease delivery of the fluid until the pressure at the discharge passage 30 has been lowered, thereafter resuming the delivery automatically. A further object is to provide a valve mechanism for elastic-fluid compressors, with which the accidental introduction of liquids or inelastic 35 fluids to the compressor-cylinder will automatically effect an enlargement of the compression-space at the end of the compression stroke of the piston, sufficient to compensate for the inducted volume of liquid, and thereby 40 prevent excessive cylinder-pressures resulting from the presence of such inelastic fluids.

In the accompanying drawings, Fig. 1 is 45 a vertical transverse section of a compressor embodying my invention, Fig. 2 is a partial longitudinal vertical section of the same, Figs. 3, 4, 5 and 6 are partly diagrammatic vertical sectional views, showing various positions in the cycle of operation of the valve-mechanism, Fig. 7 is a horizontal section on the offset plane of the line 7—7 of Fig. 3, Fig. 8 is a detail vertical section of the upper portion of the cylinder, in a slightly modified structure, and Fig. 9 is vertical 50 section of the lower portion of the cylinder, showing a modified means for limiting the

downward stroke of the valve-sleeve and lifting the same to lap position.

In the structure illustrated in Figs. 1 to 7, inclusive, I provide a crank-casing 10 having inclosed bearings 11 and 12 for a crank-shaft 13 which at one end extends through a packing-gland 14, the projecting portion of the shaft passing through a pedestal-bearing 15 and carrying a fly-wheel 16. 60 At the sides of the crank-casing other than that carrying the gland 14, are removable plates 17 which provide access to the crank and connecting-rod for inspection or adjustment. The crank 18 is connected with the 70 piston 19 by a connecting-rod 20 of ordinary form. The cylinder 21 is mounted on the upper side of the crank-casing, being secured thereto by stud-bolts 22 passing through the lower flange 23. The upper 75 portion of the cylinder is enlarged and cored to provide a jacket-space 24, to which the pipes 25 and 26 are connected at opposite sides, as shown in Fig. 2, so that water or other cooling medium may be circulated 80 through said jacket-space. Beneath the jacket-space 24, and suitably partitioned therefrom, is an annular chamber 27 having at one side of the cylinder an external opening to which is connected the suction- 85 pipe 28 through which the compressible fluid is supplied. A removable cylinder-head 29 is provided, and adjacent to said head the cylinder is counterbored to receive the fixed sleeve or bushing 30 which is of the same 90 bore or internal diameter as the lower portion of the cylinder, whereby to form substantially a continuation thereof. In the outer portion of said bushing 30, near its lower end, is an annular groove or channel 95 forming a chamber 31 which is in communication with the discharge or delivery pipe 32, the latter being disposed at the side of the cylinder opposite the suction-pipe 28.

The valve-sleeve 33 fits slidably within 100 the cylinder 21, the upper portion of said sleeve extending into the lower portion of the bushing 30, and near its upper end the sleeve has a head 34, whereby a closed space or pressure-chamber 35 is formed between 105 said sleeve-head 34 and the cylinder-head 29. The piston 19 fits slidably within the valve-sleeve below the head 34. In the walls of the valve-sleeve, below and adjacent to the head 34, are a series of ports 36 which, 110 by suitable movements of the sleeve longitudinally of the cylinder, may come into

register with ports 37 extending through the cylinder-wall to the suction-chamber 27, or into register with ports 38 which extend through the bushing-wall to the discharge-chamber 31. The piston 19 has expandible packing-rings fitting in grooves therein in the usual manner, and the valve-sleeve has similar packing-rings 39 fitting in grooves above and below the ports 36. From the discharge-chamber 31 a small port 40 is extended up through the bushing 30 to communicate with the pressure-chamber 35.

Within the crank-case, vertically alined with one side of the valve-sleeve, there is a fixed guide 41 for a push-rod 42, of which the lower end carries a shoe 43 engaging a cam 44 secured on the crank-shaft. A coil spring 45 is arranged about the rod 42 between the guide 41 and shoe 43, the pressure of said spring serving to hold the shoe against the cam. About the upper part of the push-rod, which projects above the guide 41, there is disposed a spring 46 of which the free height is such that it extends above the end of the rod. Said spring 46, by engagement with the lower end of the valve-sleeve, yieldingly resists downward movement of said sleeve, and the upper end of the push-rod 42 forms a stop or abutment for positively limiting downward movement of the sleeve.

The operation of the described structure may now be readily understood. When the valve-sleeve is in a lowered position such as shown in Figs. 3 and 4, the port 40 supplies to the chamber 35 the same pressure that exists in the discharge-pipe 32, and said pressure is exerted upon the sleeve-head 34, thus tending to move the sleeve downwardly. From the positions of the parts shown in Fig. 1, the piston commences its downward or suction stroke, and during the first part of said stroke the valve-sleeve moves with the piston. As the lower end of the sleeve engages the spring 46 the movement of the sleeve is yieldingly resisted by said spring, the resistance increasing as the spring is compressed. Should the compression of the spring 46 become sufficient to equal the head-pressure in the chamber 35, the continued downward movement of the piston will produce a partial vacuum in the chamber 47 between the piston and sleeve-head, which will cause the movement of the sleeve to be continued until the lower end thereof engages the push-rod 42, and at this position the sleeve-ports 36 will be in register with the suction-ports 37, as represented in Fig. 3. Then during the remainder of the downward stroke of the piston a charge will be drawn through the ports 36 and 37 into the piston-space or chamber 47. The cam 44 is so proportioned and arranged that just prior to the completion of the downward stroke of the piston said cam

will begin to raise the push-rod and thereby lift the valve-sleeve. The extent of movement imparted to the sleeve is such that the intake ports will be closed as the crank reaches the bottom dead-center, and the lifting of the sleeve by the cam is continued until the sleeve is in the intermediate or "lap" position shown in Fig. 4. During the upward movement of the piston the same compresses the charge in the chamber 47 until the pressure therein becomes effective in counter-balancing the head-pressure from the chamber 35, and the valve-sleeve will then commence to move upward by reason of the pressure of the spring 46, the relation of the parts being as represented in Fig. 5. By further upward movement of the piston the pressure upon the charge in the chamber 47 exceeds the head-pressure in the chamber 35, and the valve-sleeve is thereby moved up to a position at which the ports 36 come into register with the discharge-ports 38, as shown in Fig. 6. Upon the opening of the discharge-ports the excess pressure of the charge in the chamber 47 is relieved by delivery of portions thereof through said ports, so that no further movement of the sleeve occurs during the remainder of the upward stroke of the piston.

Referring now to the modified structure shown in Fig. 8, it will be noted that the discharge-pipe 32 is connected directly with the chamber above the head of the valve-sleeve, so that the discharge pressure is constantly upon the sleeve-head. The bushing 30 is omitted, and about the walls of the upper chamber, integral with the cylinder, are a plurality of inwardly extending ribs 48 of which the inner edges are bored concentrically with the cylinder, whereby to confine the packing-rings 39 in that portion of the valve-sleeve which extends up into the head-chamber. In the discharge position of the valve-sleeve the ports 36 open to the spaces between the ribs 48, said spaces forming discharge-ports which communicate with the head-chamber. The cylinder-head 29' is provided with a central lug 49 which extends down into the head-chamber, and about said lug is disposed a coil spring 50 of which the upper end is attached to the cylinder-head by means of a ring 51 engaging the upper convolution of the spring. Said spring 50 is so proportioned as to be under compression when the valve-sleeve is in the discharge position shown in the Fig. 8, and the pressure of the spring is thereby effective to move the sleeve downwardly for closing the discharge-ports when the piston begins its downward stroke, should the discharge or head-pressure upon the sleeve be insufficient to effect said closing movement. The limit of expansion of the spring 50 is reached when the sleeve is in the lap position, and during the remainder

of the downward stroke of the sleeve the spring remains suspended from the cylinder-head.

In the structure shown in Fig. 9, the crank-casing has a ledge 52 which extends in beneath the lower end of the cylinder and valve-sleeve, and said ledge supports a coil spring 46' of large diameter, positioned beneath the lower end of said sleeve. In 10 this structure the cam and push-rod are omitted, and the spring 46' forms the sole means for limiting the downward movement of the valve-sleeve and for actuating said sleeve to the lap position to close the suction-ports at the beginning of the compression stroke of the piston. This structure is suitable for use where it is desirable that the discharge-pressure of the compressed elastic fluid be automatically limited to a pre-determined maximum. Said effect is attained by suitably proportioning the spring 46', so that if the discharge-pressure is at the desired maximum the corresponding head-pressure upon the valve-sleeve will be 20 counterbalanced only when said spring is that degree of compression effected by movement of the valve-sleeve to a position at which the suction-ports are open. Under these conditions the suction ports will not 25 be closed at the beginning of the upward stroke of the piston, and the charge drawn into the piston-space during the downward stroke will be expelled through the same ports during the upward stroke, until the 30 end of the piston itself closes the sleeve-ports. The sleeve will then be lifted to the discharge position, but as the in-drawn charge was expelled through the suction ports instead of being compressed, there will 35 be nothing delivered to the discharge ports. This idling action will continue until the discharge-pressure upon the sleeve-head falls below the established maximum. When 40 this occurs, the upward pressure of the spring 46' will be sufficient to move the sleeve to the lap position at the beginning of the upward stroke of the piston, and the compressing action will be resumed.

When the pressure to be delivered by the 50 compressor is variable, the first-described structure is used, employing the cam and push-rod for raising the valve-sleeve to lap position, and with said structure the operation of the compressor is continued without 55 regard to the pressure of the discharge.

In a compressor constructed in accordance with my invention the same may be operated at a relatively high speed, whereby to attain a large output from a small, light 60 machine. High-speed operation is made possible by the smooth, balanced action of the valve mechanism, the valve-sleeve being effectively cushioned at each limit of its movement, and its motion being caused principally by variations of pressure at the op-

posite sides of the sleeve-head. The valve-sleeve is freely rotatable within the cylinder and about the piston, and the frictional contact between the parts will cause more or less rotary movement of the sleeve, which 70 may assume indiscriminately any circumferential relation to the other parts. By reason of such rotation of the sleeve, wear of the sleeve and cylinder walls will be equalized, and said parts will remain truly 75 cylindrical in form, not wearing oblong as in structures where the piston works directly in the cylinder. When the cylinder and piston become worn, the wear may be compensated by replacement of the old valve-sleeve with another of which the outside 80 and inside diameters are such as to properly fit, respectively, the worn cylinder and piston. Should liquid or incompressible fluid be accidentally drawn into the cylinder, no 85 damage to the compressor can result therefrom, as the excess pressure, resulting from the presence of the liquid, will be automatically relieved by additional lift of the valve-sleeve at the end of the compression-stroke 90 of the piston, the action of the sleeve in this respect serving the purpose of the safety-head devices commonly used for ammonia compressors in refrigeration apparatus.

Now, having described my invention, what 95 I claim and desire to secure by Letters Patent is:

1. In an elastic-fluid compressor, a cylinder having in the walls thereof inlet ports and discharge ports spaced apart longitudinally, a reciprocating piston, a valve-sleeve fitting slidably within the cylinder and about the piston, said sleeve having a head inclosing the space above the piston and having lateral ports communicating with said piston-space and adapted to register with the cylinder-ports to connect the same with the piston-space, means supplying elastic fluid pressure above the sleeve-head tending to move the sleeve downwardly in the cylinder, and means for limiting the downward movement of the sleeve and for lifting the same against the head-pressure while the piston is substantially at the end of its suction stroke.

2. In an elastic-fluid compressor, a cylinder having in the walls thereof inlet ports and discharge ports, a reciprocating piston, a valve-sleeve fitting slidably within the cylinder and about the piston, said sleeve having a head inclosing the space above the piston and having lateral ports communicating with said piston-space, said sleeve-ports being adapted to register with the inlet ports when the sleeve is at a lower limit of movement and to register with the discharge ports by movement upwardly from the lower limit through an intermediate lap position, and means supplying fluid pressure from the discharge ports to a space above the

- sleeve-head, whereby said pressure upon said head may hold the sleeve in lap position during the compression strokes of the piston until the pressure in the piston-space exceeds the pressure at the discharge ports.
3. In a structure as set forth in claim 2, a spring engageable with the valve-sleeve to resist yielding the downward movement of the sleeve as it approaches its lower limit.
- 10 4. In a structure as set forth in claim 2, a cam moving in unison with the piston, and a member controlled by said cam and engageable with the valve-sleeve to limit the downward movements thereof, said cam and
- 15 cam-controlled member being arranged to lift the sleeve to lap position when the piston is near the end of its suction strokes.
5. In a structure as set forth in claim 2, a cam-controlled member forming a positive
- 20 stop for limiting downward movement of the valve-sleeve, and a spring arranged to yieldingly resist said downward movement of the sleeve upon its approach to the positive stop.
- 25 6. In a structure as set forth in claim 2,
- a cam-controlled member forming a positive stop for limiting downward movement of the valve-sleeve, and a spring arranged to yieldingly resist said downward movement of the sleeve adjacent to the positive stop, 30 said spring and cam-controlled member adapted and arranged to lift the valve-sleeve to lap position as the piston ends its suction strokes.
7. In an elastic fluid compressor, a cylinder, a reciprocating piston, a valve-sleeve fitting slidably between the piston and cylinder-walls and having ports adapted to register with inlet and discharge ports in the cylinder-walls, and means for actuating said 35 sleeve reciprocatingly to register the sleeve-ports with the inlet ports during the suction strokes of the piston and to register the sleeve-ports with the discharge ports during a portion of the compression strokes of 40 the piston, the valve-sleeve being freely rotatable whereby to assume indiscriminately varying circumferential relations to the cylinder and piston.

CHESTER A. BAKER.
